(57) **CLAIM**

The ornamental design for a frame for floating fabric, as shown and described.

DESCRIPTION

FIG. 1 is a front elevational of a frame for floating fabric, showing my new design;

FIG. 2 is a back elevational view thereof;

FIGS. 3 and 4 are top and bottom plan views thereof, respectively; and,

FIGS. 5 and 6 are right and left side elevational views thereof, respectively.

The frame is shown with a symbolic break in its length and width. The appearance of any portion of the article between the break lines forms no part of the claimed design. The dot dash broken lines represent portions of the frame for floating fabric that form no part of the claimed design.
